FLASHLIGHT

Carl F. Joers, Los Angeles, Calif.

Application January 10, 1936, Serial No. 58,582

10 Claims. (Cl. 240—10.66)

This invention relates to flashlights of the same general character and for the same purpose as that disclosed in U. S. Patent No. 2,001,363, granted to me on May 14, 1935, and has for 5 an object the provision of a flashlight including a suitable metal body enclosed throughout with a resilient jacket of rubber or the like, except for the lens adjacent the lamp, and including a simple and novel type of switch mounted in 10 the bottom of the body and operable in opposite directions by external pressure upon the bottom, for opening and closing the circuit of the lamp at will.

Another object is to provide a switch which 15 is wholly mounted on the body of the flashlight and is operable to an equal extent and in a similar manner regardless of whether or not the jacket is in position on the flashlight body and which requires no connection with the jacket, has no 20 parts imbedded in the jacket as in the case of my said patented device and is otherwise simple of design and efficient in operation.

A further object is to provide a flashlight 25 having a telescoping body capable of extension or contraction so as to vary the length thereof for holding a selected number of battery cells by the employment of jackets of correspondingly different length.

Finally, it is an object to provide a waterproof 30 jacket which enhances the life of the flashlight and prevents damage thereto as when dropped or brought into forcible contact with hard objects. Other objects may appear as the description progresses.

I have shown a preferred form of flashlight 35 embodying my said improvements in the accompanying drawing, subject to modification, within the scope of the appended claims, without departing from the spirit thereof. In said drawing:

Fig. 1 is a top plan view.

Fig. 2 is a sectional elevation, slightly enlarged, on line 2—2 of Fig. 1;

Fig. 3 is a sectional plan on line 3—3 of Fig. 2;

Fig. 4 is a sectional plan on line 4—4 of Fig. 2; and

Fig. 5 is a perspective view of a spring metal bottom for the flashlight body, forming a switch for the lamp.

Briefly described, I generally arrange the flashlight, as shown in Fig. 2 with a metallic body B, preferably formed of a pair of telescoping cylindrical members 1 and 2, a lamp housing H of usual character fitted into the upper end of member 1 and adapted to hold a socket S and a lamp

L, a lens A at the end of housing H, batteries C, C, removably held in body B, a bottom D, forming a switch for the lamp circuit and a spring E held in compression between the lowest of batteries C and bottom D, for maintaining all of the elements of the lamp circuit in contact. Over the body B I place a removable rubber jacket J which completely encloses all of the body B and overlies the periphery of lens A so as to prevent the entrance of water and dirt 10 to the body.

The upper member 1 of the body receives at its upper end a flange 3 of a conical housing and reflector H and the lens A is held on said flange by means of an annular bead 4 which has an 15 internal annular groove 5. Socket S is attached to the bottom of housing H and lamp L is, as usual, screwed into said socket.

The bottom of body member 2 is provided with the switch member D, formed, as shown in 20 Fig. 5, with peripheral segments 6, 6 etc. and a slightly concave bottom 7, formed integrally. The segments 6 may extend upwardly and downwardly or both upwardly and downwardly as shown, in the latter event the segments being 25 folded back upon themselves and arranged in such a manner that by applying pressure to one or more of the segments at their extremities the concavity of the disc 7 will be reversed. Thus, as shown in Fig. 2, when the segments 6 are 30 pressed inwardly the portion 7 which, as seen from above, is concave in form, will become convex and will engage a central teat 8 on a plate 9 which is held in the bottom of body member 2.

The upper portions of segments 6 are spaced 35 slightly from the outer surface of member 2 so that they may be sprung inwardly for reversing the portion 7 and disengaging the same from teat 8. It is obvious that the circuit of lamp L is closed when portion 7 engages teat 8, through 40 spring E, battery cells C, socket S, lamp L, housing H and body members 1 and 2. Plate 9 has an insulating ring 10 which insulates the same from body member 2 at the bottom. Hence the movement of portion 7 to and from contact with teat 8 closes and opens the lamp circuit and the tension of the metal of which the switch D is formed serves to hold the portion 7 in either of the two positions into which it is sprung by external pressure on segments 6. Preferably the jacket conforms in shape to the bottom of the flashlight body. It is quite apparent that when pressure is applied to the bottom 11 of jacket J the central portion 7 of switch D will spring upwardly and close the 55

5 circuit of lamp L and the tension of the metal will hold the portion 7 in contact with teat 8 until pressure is applied to the upper portions of segments 6, thereby reversing the portion 7 and opening the lamp circuit. When the lower portions of segments 6 are provided they may be pressed inwardly for springing the portion 7 into contact with teat 8 in lieu of applying pressure to the bottom portion 7.

10 It is quite obvious that the body B may be extended or contracted to accommodate a selected number of battery cells C and a jacket J of sufficient length applied over the body so as to completely enclose the body against the entrance of water and dust and, additionally, providing a safeguard against breakage as when the flashlight is dropped.

15 Body member 2 has an externally formed shallow boss 12 on the periphery thereof which is 20 slideable in a vertical channel 13 formed on the member 1, as indicated in broken lines in Fig. 2, for the purpose of guiding the body members in their telescoping movement, one upon the other. Channel 13 has short right angular extensions 14 at spaced points thereon into which the boss 12 may be moved by slightly turning the body so as to lock the body members 1 and 2 at selected positions, depending upon the number of battery cells C held in the body.

25 30 What I claim as my invention and desire to secure by Letters Patent, is:

35 1. A flashlight comprising a body, a lamp mounted at an end of said body, a battery mounted within said body and connected in the circuit of said lamp, and a switch controlling said circuit and including a fixed contact member, a contact member movable by flexure thereof into and out of contact with said fixed member, and flexible peripheral portions extended in opposite 40 directions from said movable contact member and operating when pressure is applied to different ends thereof to move said movable contact into and out of engagement with said fixed contact member.

45 2. A flashlight comprising a body, a lamp at an end thereof, a battery in said body and connected in the circuit of said lamp and a switch controlling said circuit and including a fixed contact member at an end of said body and tensioned portions of which one operates when flexed to move the other into and out of contact with said fixed contact member, and a resilient jacket completely enclosing said body and switch through which pressure is applied to operate said tensioned portions, said tensioned portions being 50 located on the side and at one end of said body and being operable by pressure applied to the corresponding side and end portions of said jacket.

55 3. A flashlight comprising a tubular body, a lamp at one end of said body, a battery within said body and in the circuit for said lamp, a switch controlling said circuit and being disposed at the other end of said body and including independently flexible and connected members selectively operable on the sides and at the last named end of the body for closing said circuit, the flexible members on the sides of the body being also operable to open said circuit.

60 4. A flashlight comprising a tubular body, a lamp at one end of said body, a battery within said body and in the circuit for said lamp, a switch controlling said circuit and being disposed at the other end of said body and including independently flexible and connected members operable selectively on the sides and at the last named

end of the body for closing said circuit, the flexible members on the sides of the body being also operable to open said circuit, a jacket enclosing said body except at the end containing said lamp and having flexible portions opposite said flexible 5 members.

5 10 15 5. A flashlight comprising a body arranged to support a battery, a lamp in the circuit of said battery, and a switch controlling said battery including a fixed contact member, a circular disc forming a contact adapted to be flexed into and out of engagement with said fixed member, and flexible portions extended from the periphery of said disc and arranged to flex said disc into and out of engagement with said fixed contact when pressure is applied at spaced points thereof.

20 25 30 6. A flashlight comprising a tubular body open at its ends, a lamp mounted in one end thereof, a battery within said body and connected in the circuit of said lamp, and a switch controlling said circuit and being disposed in the other end of said body and including a fixed contact member, a concavo-convex contact member movable by flexure thereof into and out of engagement with said fixed contact member, and flexible members fixed to the periphery of said disc and operating when pressed to flex said disc into and out of engagement with said fixed contact.

35 40 45 50 55 60 7. A flashlight comprising a tubular body open at its ends, a lamp mounted in one end thereof, a battery within said body and connected in the circuit of said lamp, and a switch controlling said circuit and being disposed in the other end of said body and including a fixed contact member, a concavo-convex contact member movable by flexure thereof into and out of engagement with said fixed contact member, flexible members fixed to the periphery of said disc and operating when pressed to flex said disc into and out of engagement with said fixed contact, and a jacket surrounding said body and having flexible portions engaging said disc and said flexible members.

55 60 65 70 75 80 85 90 95 8. A flashlight comprising a tubular body open at its ends, a lamp mounted in one end thereof, a battery within said body and connected in the circuit of said lamp, and a switch controlling said circuit and being disposed in the other end of said body and including a fixed contact member, a concavo-convex contact member movable by flexure thereof into and out of engagement with said fixed contact member, flexible members fixed to the periphery of said disc and operating when pressed to flex said disc into and out of engagement with said fixed contact, said flexible members being extended at right angles to the plane of said disc and above and below the latter.

9. A flashlight comprising a tubular body open at its ends, a lamp mounted in one end thereof, a battery within said body and connected in the circuit of said lamp, and a switch controlling said circuit and being disposed in the other end of said body and including a fixed contact member, a concavo-convex contact member movable by flexure thereof into and out of engagement with said fixed contact member, and flexible members fixed to the periphery of said disc and operating when pressed to flex said disc into and out of engagement with said fixed contact, said flexible members being formed integral with said disc and operating when pressed at certain ends thereof to flex the disc into engagement with said fixed contact and operating when pressed at the other ends thereof to flex the disc out of contact with said fixed contact.

10. In a flashlight a tubular body, a lamp in 75

5 said body, a battery within said body and in the circuit of said lamp, a switch controlling said circuit and disposed at one end of said body, a tubular flexible resilient jacket enclosing said body and closing the end thereof containing said switch, said switch including a fixed contact, a flexible movable contact operating responsive to

pressure at said end of said jacket to move into engagement with said fixed contact, and means operating responsive to pressure applied against the side of said jacket adjacent said end for moving said movable contact into or out of engagement with said fixed contact. 5

CARL F. JOERS.
